US0D1082731S

(12) **United States Design Patent** (10) **Patent No.:** **US D1,082,731 S**
(45) **Date of Patent:** **** Jul. 8, 2025**

(54) **SUSCEPTOR**

(71) Applicant: **NuFlare Technology, Inc.**, Kanagawa (JP)

(72) Inventor: **Kunihiko Suzuki**, Shizuoka (JP)

(73) Assignee: **NuFlare Technology, Inc.**, Kanagawa (JP)

(**) Term: **15 Years**

(21) Appl. No.: **29/896,281**

(22) Filed: **Jun. 30, 2023**

(30) **Foreign Application Priority Data**

Jan. 11, 2023 (JP) ..... 2023-000282 D

(51) **LOC (15) Cl.** **13-03**

(52) **U.S. Cl.**

USPC **D13/182**

(58) **Field of Classification Search**

USPC D13/133, 147, 162, 182, 199; D14/433, D14/435.1, 435

CPC C30B 25/12; C23C 16/4585; H01L 21/68735; H01L 21/68785

See application file for complete search history.

Wafer Susceptor Semicorex, Date Mar. 13, 2023 [online], [retrieved Mar. 6, 2025], <https://www.semicorex.com/products/Wafer-Susceptor.html> (Year: 2023).*

Primary Examiner — Shawn T Gingrich

Assistant Examiner — Anehita E. Oribabor

(74) *Attorney, Agent, or Firm* — RANKIN, HILL & CLARK LLP

(57) **CLAIM**

The ornamental design for a susceptor as shown and described.

DESCRIPTION

FIG. 1 is a perspective view of a susceptor showing my new design

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof; and,

FIG. 8 is an enlarged end face view taken along line 8-8 thereof.

1 Claim, 7 Drawing Sheets
